UNITED STATES PATENT OFFICE.

FRIEDRICH FÖRSTE, OF LEIPSIC, GERMANY.

PRINTING-MACHINE.

SPECIFICATION forming part of Letters Patent No. 686,047, dated November 5, 1901.

Application filed March 23, 1900. Serial No. 9,910. (No model.)

To all whom it may concern:

Be it known that I, FRIEDRICH FÖRSTE, a subject of the King of Saxony, residing at Leipsic, Saxony, Germany, have invented 5 certain new and useful Improved Printing-Machines, of which the following is a description.

The present invention relates to printing-machines; and it consists of the details of 10 construction hereinafter set forth, and particularly pointed out in the claims.

In order to render the present specification easily intelligible, reference is had to the accompanying drawings, in which similar letters of reference denote similar parts throughout the several views.

Figure 1 is a vertical section on the line O O of Fig. 2. Fig. 2 is a plan of the machine; Fig. 3 a section on line N N of Fig. 1; Fig. 4, 20 a similar section to that of Fig. 1, showing the type-bed in operative position as regards the impression-drum. Fig. 5 is a part vertical cross-section of a modified form of the invention, and Fig. 6 a rear view of Fig. 5.

The shaft *h*, carrying the impression-cylinder *B*, and the shaft *b*, carrying the type-bed-carrier cylinder *F*, are both mounted to rotate in the side frames *A A*. The type-carrying drum *F* is interrupted longitudinally to receive the type-bed *C*, which is mounted by means of downwardly-extending lateral lugs on a shaft *a*, supported in the two arms *D* on the shaft of drum *F*. The type-bed is adapted to tip on the shaft *a* and 35 is further provided with downwardly-extending lugs at each end, to which is fitted a shaft *d*, running parallel to the shaft *a*. Strong springs *c c*, wound on the shafts *a* and *d*, tend to press the shaft *d* and with it the 40 end of the type-bed outward away from the shaft *b*, the said springs being held in tension by means of the arm *f* of shaft *a* resting on the shaft *b*, as will be evident from the drawings.

45 The ends of the shaft *d* are provided with rolls *g g*, which run on cam-ledges *E*, fast on the frames *A A* and prevent the type-bed from turning over when the same has passed the impression-cylinder. The rolls *g g* run 50 inside the said cam-ledges *E E*, as will be evident from Fig. 2.

The operation of the device is that when

the type-bed comes into contact with the impression-cylinder *B* the former will yield, owing to the springs *c c*, and will thus press 55 every part of the type-bed evenly and exactly onto or against the impression-cylinder, thus producing a perfectly-clear letter-press free from blur.

The inking-rollers *r* are mounted in slots *r'* of arms *r*, pivoted in the machine-frame. Thus these rolls may move and adjust themselves in their slots both to the curved surface of the drum *F* and to the flat surface of the part *C*. The full part of the drum *F* thus 65 serves as ink-distributing roll.

Another form of the invention is illustrated in Figs. 5 and 6. In this case the type-bed *C* is supported by means of frames *i i* (only one is shown, but two are generally employed) on the shaft *b*. The rear of the type-bed is provided with teeth in which the teeth of a segment *l*, fast on the shaft *b*, engage. Springs *k k*, which are fastened to the shaft *b* or grip around the same and have their ends 75 attached to the frames *i i*, retain the type-bed *C* in its normal position as regards the segment *l*. This arrangement of the type-bed *C* and the springs *k* enables the former to yield while being rotated by the segment, 80 which is fast on the shaft *b*. The yielding of the type-bed will only take place while the same is passing the drum *B*, and as soon as it has left the said drum it will be automatically adjusted as regards the carrier-segment by the springs *k*. 85

I claim as my invention—

1. In a printing-machine the combination of an ink-distributing cylinder having longitudinal slot, a type-bed pivotally mounted 90 therein and springs to normally tip it outwardly, an impression-cylinder toward which said bed is tipped and cams to return the bed to the cylinder after it has passed the impression-drum, a series of inking-rolls 95 mounted above said distributing-cylinder and means for enabling the same to adjust themselves to the curved cylinder-surface and to the flat bed substantially as described.

2. The combination of an ink-distributing 100 cylinder having longitudinal slot in its surface, a type-bed pivotally supported in said slot, arms on the drum-shaft in which the pivots of the said type-bed are supported and

springs to normally tip the said bed outwardly, an impression-cylinder toward which said bed is tipped and means for pushing the latter back toward the drum after it has 5 passed the said impression-cylinder, a series of ink-rolls mounted above the said ink-distributing cylinder and means for enabling the same to adjust themselves automatically to the curved cylinder-surface or to the

flat bed in the manner and for the purpose substantially as described.

In witness whereof I have hereunto set my hand in presence of two witnesses.

FRIEDRICH FÜRSTE.
